[57] CLAIM

The ornamental design for a handle, as shown and described.

DESCRIPTION

FIG. 1 is a perspective view taken from the top, front and left side of a handle showing my new design;
FIG. 2 is a left side elevational view thereof, the right side being the mirror image of the left side shown;
FIG. 3 is a top plan view thereof;
FIG. 4 is a front elevational view thereof;
FIG. 5 is a bottom plan view thereof;
FIG. 6 is a rear elevational view thereof; and,
FIG. 7 is a cross-sectional elevational view taken on line 7-7 of FIG. 3.

FIG. 1

FIG. 3

FIG. 2

FIG. 4

FIG. 5

FIG. 7

FIG. 6
